UNITED STATES PATENT OFFICE.

EMMA MILLER, OF YONKERS, NEW YORK.

FIELD-HOSPITAL.

1,258,694.

Specification of Letters Patent. Patented Mar. 12, 1918.

Application filed April 23, 1917. Serial No. 164,004.

To all whom it may concern:

Be it known that I, MRS. EMMA MILLER, a citizen of the United States, residing at Yonkers, in the county of Westchester and State of New York, have invented certain new and useful Improvements in Field-Hospitals, of which the following is a specification.

This invention relates to a field hospital vehicle and has for its object to provide a vehicle so constructed as to form a hospital for the accommodation of from eight to sixteen patients.

Another object of the invention is to provide a hospital vehicle having a plurality of rows of bunks and stretchers with aisles or passageways whereby all of the patients may readily be reached.

A still further object of the invention is to provide in combination with the hospital vehicle, removable stretchers whereby the wounded may be brought in from the field and the stretchers mounted in the vehicle to form a bunk, thus doing away with the necessity of removing the injured person from a stretcher to a cot or bunk.

A still further object of the invention is to provide a vehicle hospital having hinged side walls adapted to forming passageways whereby certain of the hospital bunks may be reached.

With the above and other objects in view which will hereinafter be more fully set forth, I have invented the device illustrated in the accompanying four sheets of drawings in which

Figure 1 is a side elevational view of my hospital shown opened up to receive its full capacity of patients,

Fig. 2 is a similar view showing the side walls of the device closed in,

Fig. 3 is an end elevational view of the hospital opened up as in Fig. 1, showing the flies of the canopy closed to form an inclosing tent for the hospital, certain portions of the flies being broken away.

Fig. 4 is an end elevational view of the hospital closed up as in Fig. 2, with the stretchers packed vertically,

Fig. 5 is a view similar to Fig. 4 showing several of the stretchers in position to be occupied,

Fig. 6 is a side elevational view of the hospital,

Fig. 7 is a vertical longitudinal section through the middle of the hospital,

Fig. 8 is a detail perspective view of a stretcher,

Fig. 9 is a top plan view of the hospital shown open to its full capacity on the line A—A of Fig. 7, and

Fig. 10 is an edge view of a portion of canopy or tent.

Like reference characters indicate like parts throughout the following specification and in the several views in the drawings in which 1 indicates a vehicle, which may be operated either by motive power or be drawn by horses as the case may require, and which is provided with a body 2 having a top 3 formed of longitudinal doors 4 and 5 which are horizontal when closed and form the floor of the center aisle 6 of the hospital when closed. The body 2 is preferably divided into two compartments 7 each of which is large enough to receive eight stretchers which may be stored therein when not in use. The side walls 8 and 9 of said body 2 have fixed thereto framework extensions 10 and 11, each of said framework extensions embracing uprights 12, 13, 14 and 15 which are provided on both their inner and outer surfaces with hooks 16 and 17 upon which the stretchers 18 are carried.

The side rails 19 of the stretchers are seated on the hooks. The side rails 20 of said stretchers are provided with hooks 21 which are engageable by the rings 22 and chains 23, the other ends of which are fixed to the hooks 24 or to said hooks 16 and 17 as the case may be in order that when the stretcher rails 19 are mounted upon the hooks 16 and 17, the rings 22 may be caught in the stretcher hooks 21 whereby the stretcher will be held suspended in horizontal position. There are preferably two tiers of stretchers on each side of the frames 10, the tiers 25 and 26 being spaced apart to provide the central aisle or passageway 6. The uprights 13 and 14 are sufficiently spaced apart to provide passageways between the forward and rear sets of tiers. Benches 26 are provided under the lower stretcher or bunk in each tier for the accommodation of the less seriously wounded or sick patients. In using these

benches the lower bunk in the tiers cannot be used but may be folded against framework 10 or 11 as indicated in Fig. 3.

Each of the side walls of the hospital consists of two longitudinal hinged members 27 and 28, the member 27 being hinged at its bottom edge to the framework of the

vehicle while the member 28 is hinged at its upper edge to the slats 29 forming the top framework of the device, the ends 30 of said slats extending a sufficient distance 5 beyond the framework members 10 and 11 in order that said side wall members may be closed to vertical position without being obstructed by the stretchers. Hingedly mounted upon the wall members 27 adjacent 10 their free edges are supports 32 which form legs to support said members in a horizontal position when opened out when the vehicle is at a standstill. Chains 33 connected to the upper portions of the end uprights 12, 15 have loops 34 adapted to be engaged in the hooks 35 fixed on the ends of said members 27 whereby said members may be maintained in horizontal position without the use of said legs or supports 32.

20 Hingedly connected to the free edges of the members 28 are supports 36, the free ends of which may be mounted in the sockets 37 of said members 27 whereby the member 28 may be raised to horizontal position thus 25 permitting free passage of air through the hospital. The member 27 when in its horizontal position forms a platform by means of which the outer stretchers may be mounted and whereby the patients on the stretchers 30 may be attended.

Mounted upon the top of the vehicle is a canopy 38, the flies 39, 40 and 41 of which may when desired be lowered to completely inclose the vehicle forming a tent for the 35 same. Both of these flies may be closed at the same time or only one of them may be closed as conditions require. The inner flies 40 are provided with openings 42 covered with netting 43 in order to permit passage of air into the tent and at the same time keeping insects out and in case of inclement weather the outer flies 39, 40, 41 which are imperforate may be lowered whereby rain, snow, wind, etc. will be kept 45 out. The flies 39 are doubled upon themselves at their edges to form recesses 44 to receive the edges 45 of the end flies 41 whereby a tight closure will be formed, see Fig. 10. The clasps 46 are used for the purpose of holding said edges secured together.

50 The side wall members 28 are provided with window openings 47 throughout the entire length thereof, said openings being closed preferably by translucent celluloid or light material whereby light will be freely admitted into the vehicle.

The stretchers 19, as may clearly be seen in Fig. 8, are provided with pockets 48 and 49 at both ends thereof whereby the head 60 and feet of injured persons may be held securely to the stretcher eliminating danger of the person falling therefrom while the stretcher is being handled. These pockets

also provide for securely retaining covering around the extremities of the patient. 65 Straps 50 are connected with the central parts of the stretchers whereby the covering is more securely held about the patient.

Additional cots or stretchers 51 are suspended from the underside of the side-wall 70 or platform 27 when in horizontal position by means of chains 52. The parts 53 of the handles of the stretchers are rounded so as to rotate in the annularly formed hooks 16 and 17. The heads 55 on said handles 75 hold the stretchers from accidental displacement from their supporting hooks 16 and 17. The pockets 48 and 49 are adjustable by means of the center lacing 56 by means of which they may be enlarged or reduced 80 in size and whereby they may be drawn tightly upon the bedding, etc. after a patient has been placed upon the stretcher.

Having now described my invention that which I claim to be new and desire to procure by Letters Patent is:—

1. A field hospital embracing rows of uprights and having hinged side walls spaced from the uprights which when opened up form extensions of the floor, and a plurality 90 of tiers of removably mounted stretchers some of which are supported from the sides of the uprights adjacent to the side walls and accessible from the floor extensions, substantially as described.

95 2. A field hospital embracing rows of uprights and having hinged side walls spaced from the uprights which when opened up form extensions of the floor, a plurality of tiers of removably mounted stretchers some 100 of which are supported from the sides of the uprights adjacent to the side walls and accessible from the floor extensions, and windowed flies which cover the side walls when the side walls are folded and when they are 105 opened inclose the sides of the hospital, substantially as described.

3. A field hospital embracing two rows of uprights and having hinged side walls spaced from the uprights which when 110 opened up form extensions of the floor, forward and rear sets of tiers of removably mounted stretchers some of which are supported from the sides of the uprights adjacent to the side walls and accessible from 115 the floor extensions, the forward and rear sets of tiers being spaced to form a transverse passageway communicating with the floor extensions, substantially as described.

120 In testimony whereof I affix my signature in the presence of two witnesses.

MRS. EMMA MILLER.
